CLAIM

The ornamental design for a combined bathtub and shower stall, as shown.

DESCRIPTION

FIG. 1 is a perspective view, taken from the top and front of a combined bathtub and shower stall, showing our new design;

FIG. 2 is a top plan view thereof;

FIG. 3 is a cross sectional view taken on line 3—3 of FIG. 2;

FIG. 4 is a cross sectional view taken on line 4—4 of FIG. 2; and,

FIG. 5 is a fragmentary cross sectional view taken on line 5—5 of FIG. 2.

FIG. 3

FIG. 1

FIG. 4

FIG. 2

FIG. 5
